UNITED STATES PATENT OFFICE

FRED A. NEIDER, OF AUGUSTA, KENTUCKY, ASSIGNED TO F. A. NEIDER COMPANY,
AUGUSTA, KENTUCKY, A CORPORATION OF KENTUCKY.

DEVICE FOR DOUBLE-HEADING NAILS.

1,160,191.

Specification of Letters Patent. Patented Nov. 16, 1915.

Application filed July 24, 1914. Serial No. 852,843.

To all whom it may concern:

Be it known that I, Fred A. Neider, a citizen of the United States of America, and resident of Augusta, county of Bracken, State of Kentucky, have invented certain new and useful Improvements in Devices for Double-Heading Nails, of which the following is a specification.

This invention relates to improvements in devices for double heading nails and has for an object to produce an inexpensive and simple device for adapting ordinary wire nails to use as double headed nails in erecting temporary form work or frame work such as used in concrete construction, scaffolding, etc.

A further object is to produce a device for strengthening the heads of ordinary wire nails so that the heads will not break off during the withdrawing operation, when it is desired to take down form work.

These and other objects are attained in the device described in the following specification and illustrated in the accompanying drawings in which:

Figure 1 is a longitudinal perspective view of a framework secured to a board or nail to which my double heading device has been applied. Fig. 2 is a elevation of a nail having my double heading device mounted thereon. Fig. 3 is a perspective view of the double heading device. Fig. 4 is a perspective view of the shank from which my double heading device is made.

The device embodying my invention consists of a strip of metal, see Fig. 4, rolled into cylindrical form as shown in Fig. 3. This strip is stamped out and is provided with an opening 6, and notches 7 and 8 formed in its ends. The length of the strip is made such that when it is rolled into a cylindrical form with its ends abutting together, the nail receiving opening 6, the sleeve formed thereby will be a snug fit on the shank of the nail. The notches 7 and 8 are made of such a form that when the ends of the strip are brought together, the shape of the opening 10 (see Figs. 1 and 3) formed

thereby, is the same as the opening 6. These openings are provided for the purpose of enabling the nail drawing claw of the hammer to get a better grip on the nail head when withdrawing the nail.

In use, the device is slipped over the shank of a nail of proper size and the end thereof brought into engagement with the head of the nail as shown in Fig. 2. With the device in position, the nail is driven into the wood of the form-work as shown in Fig. 1, until the inner end of the device is brought into firm engagement with the head proper of the nail, as well as the formwork, the nail being proper being spaced away from the form-work by the inner end of the sleeve, which in effect creates another head for the nail, while the outer end serves as an auxiliary strengthening head for the head proper. When it is desired to dismantle the temporary formwork, the device withdraws by breaking the claw of the hammer into engagement with the notches created by the openings 7 and 8.

The means of my device for head of the nail is held at all times in an accessible withdrawing position and at the same time the framework is held just as securely as though the head proper had been driven into direct engagement with the formwork itself. In addition to this the head of the nail is materially strengthened, since an additional thickness of metal extends entirely around the head thus doubling the thickness of the parts entering under the nail, so that the sleeve is cushioned by the operation of withdrawing the nail will be evenly distributed and in this manner prevent portions of the head from breaking away from the shank of the nail, which frequently occurs in withdrawing nails.

Having thus described my invention, what I claim is:

1. A device for producing double heads on nails consisting of a cylindrical sleeve having notches cut in its sides at diametrically opposite sides and forming a way between them.

2. The combination of a nail, a cylindrical sleeve mounted upon the shank of the nail and having depressions on opposite sides forming a way for a claw hammer and having its end contacting with the underside of the head of the nail.

In testimony whereof, I have hereunto

subscribed my name this 21st day of July, 1914.

FRED A. NEIDER.
